STUD WELDING TOOL

Howard N. Wieland, Amherst, and Steve Spisak, Elyria,
Ohio, assignors to Gregory Industries, Inc., Lorain,
Ohio, a corporation of Michigan

Filed Apr. 22, 1968, Ser. No. 11,543

Term of patent 14 years

U.S. Cl. D26—1
Int. Cl. D8—02

FIG-1-

FIG-5 -

FIG-6 -

FIG. 3-

FIG. 2-

FIG. 4-

FIG. 1 is a perspective view of a stud welding tool showing our new design;

FIG. 2 is a left side elevational view;

FIG. 3 is a top view;

FIG. 4 is a bottom view;

FIG. 5 is a front elevational view with parts otherwise shown in dotted lines being removed; and

FIG. 6 is a rear elevational view.

The dominant features of our design reside in the portions shown in full lines.

We claim:

The ornamental design for a stud welding tool, substantially as shown and described.
